UNITED STATES PATENT OFFICE.

SCOTT RUSSELL McCONNELL, OF WICHITA FALLS, TEXAS.

ROPE-SOCKET.

Specification of Letters Patent. Patented May 28, 1918.

1,267,430.

Application filed October 9, 1917. Serial No. 195,561.

To all whom it may concern:

Be it known that I, SCOTT RUSSELL McCONNELL, a citizen of the United States, residing at Wichita Falls, in the county of 5 Wichita and State of Texas, have invented certain new and useful Improvements in Rope-Sockets; and I do hereby declare the following to be a full, clear, and exact description of the invention, such as will enable others skilled in the art to which it 10 appertains to make and use the same.

This invention relates to new and useful improvements in rope sockets for use in connection with oil well drilling bits, and 15 the primary object of the invention is to provide a rope socket of this character which can be quickly, easily and conveniently adjusted to provide a swivel or nonswivel socket as desired.

20 A further object of the invention is to provide a simple and inexpensive rope socket which is so constructed that it will take care of or compensate for the jar and rebound action of the socket and bit with 25 respect to the line wire rope attached to it, incident to drilling.

With these and other objects in view as 30 will appear as the description proceeds, the invention comprises the various novel features of construction, combination and arrangement of parts as will be more fully described hereinafter and afterward specifically claimed.

35 Referring to the drawings: Figure 1 represents a side elevation of my improved rope socket, and

Fig. 2 represents a vertical longitudinal sectional view therethrough.

Similar characters of reference are used 40 to denote corresponding parts throughout the following description and accompanying drawings.

In order that the construction and operation of the invention may be readily comprehended, I have illustrated an approved embodiment thereof in the accompanying drawings, and will now proceed to fully describe the same, in connection with said drawings, in which 1 indicates the cylindrical body of the rope socket, the upper end of which is provided with a reduced neck 2, while the lower end is recessed on opposite sides as at 3 to provide wrench 50 holds whereby the socket may be conveniently and securely attached to the well drilling bit.

The body 1 is provided with a central longitudinal bore 4 which communicates with a larger bore 5 arranged substantially intermediate the ends of the body. An entrance opening 6 extends transversely through the vertical wall of the body and communicates with the larger bore 5, that portion of the body 1 at the lower end of the entrance opening 6 being beveled or inclined inwardly as indicated by 7. The body 1 has formed therein a key way 8 extending longitudinally of and communicating with the larger bore 5.

The lower end of the body 1 is provided centrally with a conical threaded socket 9 adapted to receive the threaded end of the well drilling bit to securely attach the socket to the latter.

A cylindrical swivel member 10 is slidable mounted within the larger bore 5 and is provided in its upper end with a restricted bore 11 communicating with a tapered bore 12, the lower end of the line wire rope extends freely through the body bore 4 and the restricted bore 11 and is rigidly and wedgingly secured to the member 10 within the tapered bore 12 thereof without the use of Babbitt or other similar metal. This swivel member 10 is provided with a removable key 14 in its vertical side wall which projects laterally into the key way 8 having vertical sliding movements therein. When it is desired to use the socket as a non swivel socket, the key 14 is used but 85 when it is desired to use the socket as a swivel socket the key is removed in a manner that will be presently explained.

15 indicates a cylindrical plug having a tapered stem 16 removably positioned within the upper flared end of the bore 4 so that the plug will rest on the bottom of the larger bore 5. This plug 15 is removable through the entrance opening 6, but is normally held in the position shown through the medium of a pin 16' which extends transversely 95 through the body 1 and a groove 17 formed in the upper surface of the plug.

When it is desired to convert the socket 100 into a swivel socket the pin 16' and plug 15 are removed so that the swivel member 10 can be also removed through the entrance opening 6 to remove the key 14, after which the parts can be reassembled into operative 105 relation to each other.

110 It is to be noted that the length of the bore 5 is slightly greater than the length

of the swivel member 10 so that the latter may have a slight amount of sliding movement therein to compensate for the jar and rebound movement of the body 1 with respect to the rope 13 in the use of the socket incident to drilling.

If desirable the body 1 may be provided with an opening 18 establishing communication between one of the recesses 3 and the 10 internal bore 5 whereby sediment or other foreign matter may conveniently drain from the bore 5.

Having described my invention, what I claim as new, is:

- 15 1. A rope socket comprising a cylindrical body having a central longitudinal bore communicating with a larger bore arranged intermediate its ends, said body being provided with an entrance opening in its vertical wall communicating with said larger bore, a swivel member slidably mounted in said larger bore, a rope extending freely through the upper end of said body and rigidly attached to said swivel member,
- 20 25 means to prevent independent rotation of the swivel member with respect to said body, and means for maintaining said swivel member within said larger bore.
2. A rope socket comprising a cylindrical body having a central longitudinal bore communicating with a larger bore arranged substantially intermediate its ends, said body having an entrance opening in its vertical wall communicating with said larger bore, a swivel member vertically removable within said larger bore, a line rope extending through the upper end of said body and rigidly attached to said swivel member, detachable means carried by said swivel member to prevent independent rotation of the swivel member with said body, and means for maintaining the swivel member within said larger bore.
- 30 35 40 45 3. A rope socket comprising a cylindrical body having a central longitudinal bore communicating with a larger bore arranged substantially intermediate its ends, said body being provided in its vertical wall with an entrance opening communicating with said

larger bore and a key way communicating 50 with and extending longitudinally of said larger bore, a swivel member vertically movable within said larger bore, a line wire rope extending through said body and rigidly attached to said swivel member, a key removable 55 carried by said swivel member and projecting into said key way, and means for normally maintaining the swivel member operatively within said larger bore.

4. A rope socket comprising a cylindrical 60 body having a central longitudinal bore communicating with a larger bore arranged intermediate its ends, said body being provided with an entrance opening in its side wall communicating with said larger bore, a 65 non-rotatable swivel member vertically movable within the upper end of said larger bore, a line wire rope extending freely through the upper end of said body and rigidly connected to the swivel member, a plug 70 removably positioned within and on the bottom of said larger bore, and means for rigidly holding the plug in said position.

5. A rope socket comprising a cylindrical body having a central longitudinal bore 75 communicating with a larger bore arranged intermediate its ends, said body being provided with an entrance opening in its vertical wall communicating with said larger bore, a swivel member slidably mounted in 80 said larger bore and provided in its upper end with a central longitudinal restricted bore communicating with a tapered bore in its lower end, a rope extending freely through the upper end of said body, the restricted bore of said swivel member and rigidly and wedgingly secured within said tapered bore, means to prevent independent rotation of the swivel member with respect to said body, and means for maintaining 85 said swivel member within said larger bore.

In testimony whereof I have signed my name to this specification in the presence of two subscribing witnesses.

SCOTT RUSSELL McCONNELL.
